KNOCKDOWN DISPLAY STRUCTURE

Carl A. Elsbernd, Cincinnati, Ohio, assignor to Burton-Rodgers Inc., Elmwood, Cincinnati, Ohio, a corporation of Ohio

Application January 27, 1954, Serial No. 406,540

2 Claims. (Cl. 248—197)

This invention relates to a knockdown display structure of known design wherein a plurality of panels (usually two) are hinged together and provided with interlocking means to hold the panels in open operative edge aligned position and an intermediate leg providing an easel-like structure. Such display structures have in the past been provided with leg elements which were detachably secured thereto and for shipment or transportation the brace, the intermediate leg and the legs were detached, the panels folded together and the two legs were then attached to the folded structure to form end closures and the brace and intermediate leg were attached to the structure to form side closures. A display structure as outlined above is shown in the Tucker Patent, No. 2,641,431 dated June 9, 1953.

It is an object of the present invention to provide a structure for similar purposes and uses which will be simpler and less expensive to manufacture. It is another object of the invention to provide such a structure which in the knockdown condition forms a more perfect case or crate so that the material displayed thereon is better protected. It is still another object of the invention to provide a structure along the lines mentioned which can be more rapidly set up or knocked down.

These and other objects of the invention which will be pointed out in more detail hereinafter or which will become apparent to one skilled in the art upon reading these specifications, I accomplish by that certain construction and arrangement of parts of which I shall now describe an exemplary embodiment.

Reference is made to the drawings forming a part hereof and in which:

Figure 1 is a rear elevational view of a display structure according to my invention in erected condition with parts broken away.

Figure 2 is a cross sectional view of the same taken on the line 2—2 of Figure 1.

Figure 3 is an exploded view similar to Figure 2 showing the brace removed and the panels folded together.

Figure 4 is a cross sectional view taken on the line 4—4 of Figure 1.

Figure 5 is a cross sectional view through the intermediate leg taken on the line 5—5 of Figure 1.

Figure 6 is an elevational view of the display in knockdown condition and ready for transportation or shipment.

Figure 7 is a cross sectional view taken on the line 7—7 of Figure 6.

Figure 8 is a fragmentary cross sectional view taken on the line 8—8 of Figure 6 on an enlarged scale, and

Figure 9 is a fragmentary cross sectional view taken on the line 9—9 of Figure 6 also on an enlarged scale.

Briefly, in the practice of my invention I provide a plurality of panels which are generally rectangular in shape and which are hinged together along their adjacent long sides. It will be understood that some sort of display is provided on the front face of these panels. A cross brace is provided for holding the panels in open operative edge-aligned position and an intermediate leg

is hinged and removably attached to the structure near the top to provide an easel arrangement. Each of the panels is provided with a telescoping adjustable leg member and the intermediate leg is provided with an extensible and adjustable supplementary leg and the short edges of the panels are flanged. When it is desired to knock down the display, the telescoping legs are telescoped out of the way and secured by clamps, the extensible supplementary leg is retracted and secured in position and the intermediate leg and brace are removed from the panels. The panels are then folded together so that the flanges on the short edges of the respective panels meet in abutting relation to constitute end closures for the knockdown display and the brace and intermediate leg constitute side closures or bottom and top closures for the knockdown display.

Referring more in detail to the drawings, the panels of more or less conventional design are indicated at 10 and 11. The panels consist of a framework comprising the longitudinal members 12, 13 and 14, 15 and the cross members 16, 17 and 18, 19. The members 16, 17, 18, 19 are provided with the flanges 20, 21 and 22, 23. The flanges are desirably protected by finishing strips 24.

The panels 10 and 11 are hinged together by means of hinges 25 and from a consideration of Figures 2 and 3, it will be apparent that they may be folded together as in Figure 3 or opened up as in Figure 2. When folded together as in Figure 3, the flanges 21 and 23 abut each other as do the flanges 20 and 22.

In order to retain the panels 10 and 11 in open operative edge-aligned position, I employ a brace consisting of an elongated board or the like 26 which may be reinforced as by means of a member 27 secured thereto. The brace 26 and the panels 10 and 11 are provided with cooperative interlocking elements 28 and 29, as is well known, and blocks 30 are secured to the backs of the panels below the members 29 to hold the brace 26 in position. The member 26 is also provided with hasps 31, one adjacent each end which cooperate with certain staples as will hereinafter be pointed out. Pins or dowels 32 are also provided on the brace 26 for reasons which will be pointed out hereinafter.

The leg members for the structure comprise the hairpin-like rods 33 which pass through holes provided in the frame elements 17 and 19 respectively and which may be clamped in a desired position of adjustment by means of the clamps 34 and the wing nuts 35. This construction is perhaps best seen in the cross-sectional view of Figure 8. In use, the legs 33 may be extended a desired amount and clamped in position. When it is desired to knock down a display, the clamps are loosened and the legs 33 retracted and then reclamped, as best seen in Figure 6.

In order to provide an easel arrangement there is shown an intermediate leg 36. This intermediate leg is provided at each end with a block 37 to which is secured a hasp 38. On the back of one of the panels, a staple 39 is secured to a block 40 and just above the block 40 is provided an abutment block 41 having a sloping lower surface at 42. The intermediate leg 36 is secured to the panel by engaging the upper hasp 38 over the staple 39 and locking it with a suitable pin (not shown).

The intermediate leg 36 is provided with the flanges 43 which have sloping ends as at 44, the flanges 43 acting as skids for the knockdown display. An extensible supplementary leg is shown at 45 and it is provided with the slots 46. Bolts 47 passing through the slots 46 of the member 45 and through holes in the intermediate leg 36 clamp the extensible leg 45 in a desired position of adjustment. Wing nuts 48 may be provided for quick operation.

In Figure 4, the extensible leg 45 is shown as being extended to a point to cause the panels 10 and 11 to occupy

a substantially vertical position. When it is desired to knock down a display, the extensible leg 45 is retracted and as will be clear from a consideration of Figure 5, the extensible leg lies wholly below the tops of the flanges 43 which serve as the skid members so that the extensible leg in no way interferes with the skidding of the display over a floor surface.

The intermediate leg 36 is braced by means of the hooks 49 which are secured to the member 36 by the eyes 50 and which engage hasps 51 secured to the backs of the panels 10 and 11 respectively.

From a consideration of Figure 1, it will be noted that the frame members 12 and 15 are provided with holes 32a which accommodate the dowels 32 on the brace 26 when the structure is knocked down. It will also be noted that the panel 10 is provided with the staples 31b and 38b at its upper end and the panel 11 is provided with the staples 31a and 38a at its lower end. It will have been observed that the hasps 31 on the member 26 are laterally offset and it will now be clear that when the panels 10 and 11 are folded together and the member 26 is placed on top of the knockdown structure, as seen in Figure 6, the dowels or pins 32 enter the holes 32a and the hasps 31 may engage with the respective staples 31a and 31b. It will also be clear that it makes no difference if the member 26 is reversed end for end because the offset hasps will still engage the respective staples. The hasps may then be secured with pins, padlocks or the like if desired. The member 26 thus constitutes a side or top closure for the knockdown display.

The bottom closure and skid is provided by the intermediate leg 36 with the supplementary leg 45 retracted and with the hasps 38 engaging respectively the staples 38a and 38b. These hasps 38 are likewise laterally offset so that the hasp 38 at one end engages the staple 38b secured to the panel 10 while the hasp 38 at the other end engages the staple 38a secured to the panel 11.

From the foregoing, it will be seen that there are only two pieces which must be detached from the erected display in order to convert it to knockdown condition and therefore the operation of erecting or knocking down the display can be accomplished with great speed. Also in its knockdown condition, the display is fully protected by the brace 26 at the top, the intermediate leg 36 at the bottom and the cooperating flanges 20, 21, 22 and 23 at the ends.

It will be understood that modifications and variations may be made without departing from the spirit of my invention and I therefore do not intend to limit myself except as set forth in the claims which follow.

Having now fully described my invention, what I claim as new and desire to secure by Letters Patent is:

1. A knockdown display unit comprising a plurality of panels hingedly secured together, an elongated brace, interengaging locking means carried by the rear of said panels and the forward side of said brace for detachably securing said brace to said panels to thereby hold the

latter in open, operative, edge-aligned position, a pair of legs telescopically and adjustably secured, one to each of said panels, an intermediate leg, means hingedly and detachably securing said intermediate leg to the upper portion of said unit, means limiting the angular adjustment of said intermediate leg relative to said unit, said panels having flanges along their shorter edges such that when said panels are folded together along their meeting long edges, said flanges meet to form end closures for said unit, and correlated means carried by said brace, and intermediate leg and marginal portions of said panels for securing said intermediate leg and brace to the long sides of said folded panels to constitute side closures for said unit, one of said panels having a fastening element adjacent each end of one of its short sides, another of said panels having a fastening element adjacent each end of the short side at the other end with respect to said one panel, and said brace and intermediate leg having fastening elements at their ends cooperating with the fastening elements on said panels, the fastening elements at one end of said brace and intermediate leg being laterally offset with respect to the fastening elements at the other ends of said brace and intermediate leg, respectively.

2. A knockdown display unit comprising a plurality of panels hingedly secured together, an elongated brace, interengaging locking means carried by the rear of said panels and the forward side of said brace for detachably securing said brace to said panels to thereby hold the latter in open, operative, edge-aligned position, a pair of legs telescopically and adjustably secured, one to each of said panels, an intermediate leg, means hingedly and detachably securing said intermediate leg to the upper portion of said unit, means limiting the angular adjustment of said intermediate leg relative to said unit, said panels having flanges along their shorter edges such that when said panels are folded together along their meeting long edges, said flanges meet to form end closures for said unit, and correlated means carried by said brace and intermediate leg and marginal portions of said panels for securing said intermediate leg and brace to the long sides of said folded panels to constitute side closures for said unit, each of said panels comprising a frame, each leg of said pair comprising a hairpin-like rod passing through spaced holes in said frame, and clamping means on said panel for clamping said leg in a desired position of extension or retraction, said leg when retracted lying substantially flush with the back of said panel.
